A. G. HUPFEL,
GOLF BALL MARKING DEVICE,
APPLICATION FILED FEB. 7, 1921.

1,395,418.

Patented Nov. 1, 1921.

UNITED STATES PATENT OFFICE.

ADOLPH G. HUFFEL, OF RENO, NEVADA.

GOLF-BALL-MARKING DEVICE.

1,395,418.

Specification of Letters Patent.

Patented Nov. 1, 1921.

Application filed February 7, 1921. Serial No. 443,120.

To all whom it may concern:

Be it known that I, ADOLPH G. HUFFEL, a citizen of the United States, resident of Reno, county of Washoe, and State of Nevada, have invented new and useful Improvements in Golf-Ball-Marking Devices, of which the following is a specification, the principle of the invention being herein explained and the best mode in which I 10 have contemplated applying that principle, so as to distinguish it from other inventions.

My invention relates to golf-ball marking devices, the object being to produce a 15 device of said character, the construction of which may be economically effected and which will be efficient in the performance of its function. The said invention consists of means hereinafter fully described and particularly pointed out in the claims.

I am aware that golf-ball marking devices have heretofore been constructed and patented, but the said devices have either been so complicated as to make the expense of 25 production prohibitively great, or they have been of a character which, while simple, distort the ball and are consequently objectionable. In carrying out my invention, I have provided an oscillatory type-carrying member which coöperates with a base 30 upon which a ball may roll, to impress, during rolling contact, the required marking, the said oscillatory member being so mounted and constructed that the types may be 35 readily inserted or removed, and the said base being also adjustable so as to permit the device to be used in connection with different sizes of balls.

The annexed drawing and the following 40 description set forth in detail certain means embodying my invention, the disclosed means, however, constituting but one of the various mechanical forms in which the principle of the invention may be applied.

45 In said annexed drawing:

Figure 1 represents a full-sized side elevation of a marking device embodying my invention, and showing the parts in the position which they occupy after a marking 50 operation has just been completed.

Fig. 2 represents a side elevation, with the parts in the position which they occupy just prior to the marking operation.

Fig. 3 represents a plan of the device.

Fig. 4 represents a section taken upon 55 the plane indicated by line IV—IV in Fig. 1.

Fig. 5 represents a section taken upon the plane indicated by line V—V in Fig. 3.

Fig. 6 represents a section taken upon 60 the plane indicated by line VI—VI in Fig. 5.

Fig. 7 represents a detail section taken upon the plane indicated by line VII—VII in Fig. 5.

Fig. 8 represents three views of one of 65 the types used in connection with the device.

Fig. 9 represents a full-sized golf-ball after having been marked.

The illustrated embodiment of my invention comprises a main frame-member 1; an oscillatory type-carrying lever 2 mounted upon said main frame-member; an adjustable base 3; and an inking roller 4 75 mounted upon said frame.

The frame-member 1 consists of two U-shaped and similar plates 5—5, which are secured to each other in parallelism by rivets 6—6, and other separating and securing means, as will hereinafter appear, but removed from each other to form an intermediate space 8, Fig. 3.

The upper end of the frame-member is widened, as shown, and formed with an inner convex surface 9, whose curvature is circular and has its center in the axis of the journal-screw 10 upon which the lever 2 is mounted. This screw, as shown in Fig. 1, is placed near the extremity of the upper end portion of the frame-member, and is shouldered, as at 11, its intermediate portion 12 acting as the bearing for the said lever, and also acting as a means for holding together and separating the upper ends 80 of the plates 5—5, see Fig. 6.

The lever, as shown, is mounted between said plates and upon said journal-screw, and is provided with a laterally placed stoppin or screw 13, which is removable, but which, while in place, limits the oscillation of the lever, the two extreme and so limited positions being shown in full lines in Figs. 1 and 2 respectively. The outer end of arm 14 of the lever is intersected by a type-recess 15 having end walls 16'—16' converg-

ing toward the axis of the lever, as shown in Fig. 5. When the stop 13 is removed, the lever may be swung into the position shown in dotted lines in Fig. 2, in which position the recess 15 clears the frame-member and is thus exposed so that the types may be inserted laterally into or removed from such recess. Each of the types is provided at one side with a slot 16, and the one side of 10 the lever arm is similarly slotted as at 17—17, Figs. 5 and 7, to receive a fixed wire holder 18, having two bent ends 19—19 for insertion and riveted into small holes 20—20, whereby the types are prevented from 15 falling out radially. The depth of the lever is such that it will correspond with the depth of the space 8, but move freely therein, the inset position of the wire holder 18 eliminating any interference with such requirement, as will be readily seen.

20 The types have end walls 21—21 of the same degree of convergence as the end walls 16'—16' of the recess 15, so that they fit snugly and securely therein and are of a 25 length such that during their travel they will project beyond the convex surface 9, as shown in Fig. 2. In the normal or printing operation of the device, the stop 13 is in place, so that the lever does not reach a 30 position in which types are exposed laterally excepting only at their ends.

An inking roller 4 is mounted in the frame-member between the plates, as shown in Fig. 5, and lies in the normal path of 35 movement of the faces of the types, so that the latter will be inked upon each oscillatory movement of the lever.

Upon the other end of the frame and opposite the axis of the lever 2, is the base or 40 saddle 3 of Y-shaped cross-section. The lower portion 23 of this base fits between the plates 5—5 in the space 8, but is movable therein, and is provided with two curved slots 24—24 through which pass two supporting rivets 25—25, Fig. 5. These slots are formed so that when they are engaged 45 by the rivets at either of their opposite ends, the base will be held in one of two positions, the one being shown in full lines in Fig. 5, 50 and the other in dotted lines.

The upper portion of the base is formed of two wings 26—26, diverging outwardly and whose upper surfaces 27—27 converge to form an interior angle. These surfaces 55 are furthermore curved, Fig. 5, such curvature being circular and having its axis substantially in the axis of the journal-screw 10. Such upper surfaces are preferably serrated, as shown, to prevent slippage.

60 Assuming the parts to be in the position shown in Fig. 2, the distance from the base 3 to the curved surface 9 is substantially equal to the diameter of a standard "floater" golf-ball. A ball being now inserted in the 65 space between said base and surface, as

shown in dotted lines, rests and is centered upon the said base. The outer arm 28 of the lever 2, now being used as a handle, the type may be moved over the adjacent surface of the ball by rolling contact; the said 70 ball rolling upon the surface of such base, until the stop 13 comes into contact with the frame, as shown in Fig. 1, the ball being, however, still held in position between the base and surface 9. During this movement, 75 the types are inked, and upon reversing the described movement of the lever, the ball is rolled back to its initial position, from which it may be removed from the device, with the required marking thereon.

80 When it is desired to mark a "sinker" the base is moved up into the position shown in dotted lines in Fig. 5.

A suitable thumb piece 29 may be secured to one side of frame 1, to facilitate proper 85 holding of the device during the above-described operation.

As shown in the drawing, I prefer to make the curvature of the lateral surface of the frame-member 1, circular and similarly the 90 lateral curved surface of the lever 2 also circular so that when the device is not in its operative position as shown in Fig. 1, the curvature of the said lever will form a continuation of the curvature of the frame-member. The length of this lever is also made such that in such position it will substantially complete the circumference of a 95 circle. This gives the device, when being carried about by the user, a highly desirable 100 and convenient form. It also provides a form which is readily held in the hand, while being operated, without discomfort.

What I claim is:

1. In a golf-ball marking device, the combination of a main frame-member; a base-member mounted upon said frame-member and having a fixed surface upon which a ball is adapted to roll; and an oscillatory lever mounted upon said frame-member and provided with marking means.

2. In a golf-ball marking device; the combination of a main frame-member; a base-member mounted upon said frame-member and having a fixed curved surface upon which a ball is adapted to roll; and an oscillatory lever mounted upon said frame-member and provided with marking means.

3. In a golf-ball marking device; the combination of a main frame-member; a base-member mounted upon said frame-member and having a fixed curved surface upon which a ball is adapted to roll; and an oscillatory lever mounted upon said frame-member and provided with marking means; the curvature of said surface having its center in the axis of said lever.

4. In a golf-ball marking device, the combination of a main frame-member; a base-member mounted upon said frame-member

and having a surface upon which a ball is adapted to roll; and an oscillatory lever mounted upon said frame-member and provided with marking means; said base-member being adjustable toward and from the axis of said lever.

5. In a golf-ball marking device, the combination of a main frame-member; a base-member mounted upon said frame-member 10 and having a curved surface upon which a ball is adapted to roll; and an oscillatory lever mounted upon said frame-member and provided with marking means; said base-member being adjustable toward and from 15 the axis of said lever.

6. In a golf-ball marking device, the combination of a main frame; a base-member mounted upon said frame and upon which a ball may roll; a type-carrying member 20 movably mounted upon said frame and adapted to coöperate with said base to impress said type upon such ball; said type being laterally removable from said member; and type confining means carried by 25 said frame for preventing lateral movement of said type.

7. In a golf-ball marking device, the combination of a main U-shaped frame-member comprising two plates and suitable separating and securing means therefor; a lever 30 mounted on one arm of said frame-member and between said plates; marking types mounted on said lever; and a base mounted upon the other arm of said frame member 35 opposite the said lever, and upon which a ball is adapted to roll.

8. In a golf-ball marking device, the combination of a main U-shaped frame-member comprising two plates and suitable separating 40 and securing means therefor; a lever mounted on one arm of said frame-member and between said plates; marking types mounted on said lever; and a base mounted between said plates on the other arm of the 45 frame-member, and upon which a ball is adapted to roll.

9. In a golf-ball marking device, the combination of a main U-shaped frame-member comprising two plates and suitable separating 50 and securing means therefor; a lever mounted on one arm of said frame-member and between said plates; marking type mounted on said lever; a base mounted upon the other arm of said frame member upon 55 which a ball may roll; and an inking roller mounted between said plates and lying on the path of movement of said types.

10. In a golf ball marking device, the combination of a main frame-member; a base- 60 member mounted upon said frame-member and having a fixed curved surface over which a ball is adapted to roll; an oscillatory lever pivoted upon said frame-member and having a curved surface engageable 65 with the ball; marking means carried by

one of said surfaces; the center of curvature of said surfaces being substantially at the pivot of said lever, and means for limiting oscillatory movement of said lever.

11. In a golf-ball marking device, the 70 combination of a main frame-member of U-shaped form; a base-member mounted upon said frame-member and having a fixed surface upon which the ball is adapted to roll; and a manually operable oscillatory 75 lever mounted upon said frame-member and provided with marking means; said lever being curved so as to provide a lateral surface forming a continuation of the curvature of the lateral surface of the main frame- 80 member.

12. In a golf-ball marking device, the combination of a frame-member; a base-member mounted upon said frame-member and having a fixed surface upon which a 85 ball is adapted to roll; and a manually operable oscillatory lever mounted upon said frame-member and provided with marking means; and means for limiting the oscillation of said lever; said main frame-member 90 consisting of two spaced plates between which said lever is mounted; the means for limiting the oscillation of said lever being arranged so that in one of the extreme positions of such lever the marking means will 95 be inclosed by said plates.

13. In a golf ball marking device, the combination of a main U shaped frame; a base-member having a curved surface over which a ball is adapted to roll mounted upon 100 one arm of said frame; an oscillatory lever pivoted to the other arm of said frame and having a curved surface provided with marking means; the center of curvature of said surfaces being substantially at the pivot of 105 said lever.

14. In a golf ball marking device; the combination of a frame; a serrated V shaped base-member mounted on said frame upon which a ball is adapted to roll; and means 110 for rolling said ball along said base-member and for simultaneously impressing a mark thereon.

15. In a golf ball marking device, the combination of a U shaped frame; a longitudinally curved serrated V shaped base-member secured within one arm of said frame; and an oscillatory lever pivoted to the other arm of said frame and having a curved surface provided with marking 115 means; the centers of curvature of said surfaces being substantially at the pivot of said lever.

16. In a golf ball marking device, the combination of an open ended frame, a base-member over which a ball is adapted to roll mounted within said frame; a lever pivoted to said frame opposite said base-member and having an arm adapted in one position of the lever to close the open end of said frame; 120 125 130

and ball engaging marking means carried by said lever adapted to roll said ball toward the open end of said frame as said lever arm is swung away from said open end of the 5 frame.

17. In a golf ball marking device, an open ended frame comprising two spaced plates; a lever pivoted between said plates; marking type carried upon the inner end of said 10 lever; the outer end of said lever being movable to a position across the open end of said frame; and a base-member carried by said frame adapted to support a ball in position to be engaged by said marking type, said 15 type lying wholly within the spaced plates

of the frame when said lever is positioned across the open end of said frame.

18. In a golf ball marking device, a frame comprising a pair of spaced plates; ball supporting means carried by said frame; 20 type carrying means movably supported between said plates; and an inking roller mounted between and wholly within the edges of said plates; said type carrying means being movable to a position in which 25 the type thereon is positioned wholly within said plates.

Signed by me this 25th day of January, 1921.

ADOLPH G. HUFFEL.
